UNITED STATES PATENT OFFICE.

SECONDO L. CASELLA, OF SAN FRANCISCO, CALIFORNIA, ASSIGNOR, BY DIRECT AND MESNE ASSIGNMENTS, TO W. F. BARNES COMMERCIAL CO., OF SAN FRANCISCO, CALIFORNIA, A CORPORATION OF CALIFORNIA.

BASKET-MAKING-MACHINE ATTACHMENT.

No. 894,597.

Specification of Letters Patent.

Patented July 28, 1908.

Application filed June 16, 1906. Serial No. 322,044.

To all whom it may concern:

Be it known that I, SECONDO L. CASELLA, citizen of United States, residing in the city and county of San Francisco and State of California, have invented new and useful Improvements in Basket-Making-Machine Attachments, of which the following is a specification.

My invention relates to an apparatus which is designed for the manufacture of baskets such as are formed by crossing thin veneers transversely, bending them to form the sides, and completing the basket by means of a binding strip around the top edges.

My present invention relates to means for feeding the veneers to the former by which the veneers are bent and the basket assembled; and subsequently removing the completed baskets from the former and delivering them from the machine.

It consists in a combination of mechanism actuated in unison with the basket forming mechanism and in details of construction which will be more fully explained by reference to the accompanying drawings, in which—

Figure 1 is a plan view of the apparatus. Fig. 2 is a side elevation showing the feed and discharge mechanism. Fig. 3 is a view taken from the opposite side to Fig. 2 showing particularly the feed mechanism. Fig. 4 is a transverse section showing valve and lever.

I have only shown so much of the basket assembling device as is necessary to illustrate the attachments which are used therewith, and in which A is a former over which the veneers are bent by the vertical reciprocation of a rectangular frame B which is located above the former and has such shape that when the veneers have been properly placed upon the part A, the depression of the part B will fold the veneers over the part A, and thus complete the outline of the basket.

The veneers are supplied to the former as follows: 2 and 3 are containers within which the thin veneers are placed, such veneers being represented at 4. In order to deliver these veneers from the containers and place them upon the former I employ an apparatus which is constructed as follows: 5 is a tube having an opening 6 at its outer end, and this opening is disposed beneath the lower surface of the veneers 4; these veneers being normally held in position by a light

frictional or other support 5^a sufficient to normally maintain them in place, but which may be overcome by a vacuum produced within the pipe 5 when the opening 6 is brought into contact with the veneer so that by oscillating the pipe when the opening is brought into contact with the bottom of one of the veneers, an adhesion will be produced by opening a suction valve at the proper instant, and by then drawing the oscillating pipe in the other direction, the single veneer adhering to the pipe opening will be removed from the remainder, and brought into line with the surface of the former. A reciprocating mechanism acting in unison with this apparatus then forces the veneer forward and places it upon the former. There are two of these devices standing at right angles with each other, and by their operation the veneers are placed transversely upon the former, and the remainder of the operation completed by the folding mechanism.

The pipe 5 has a joint as shown at 7 which connects it with a pipe 8, and this is here shown as connected by a pipe 9 with a vacuum tank or apparatus as at 10. It will be understood that any arrangement of these pipes may be made which will suit the construction of the machine, the object being in any event to connect the oscillating suction pipe 5 with a means for producing a vacuum therein. This vacuum is controlled by means of valves located at 11 and having a crank or equivalent connection 12 by which the valves are alternately opened when the mouth 6 is brought into contact with the veneer, and closed to cut off the vacuum or suction when the part has been depressed and in readiness to deliver the veneer to the former.

I have here shown an actuating mechanism constructed as follows: 13 is a lever fulcrumed as at 14'. Upon this lever is carried an anti-friction roller or spur 15 which engages with the channel of a cam 17 which is mounted upon a driving shaft 18, by the revolution of which the cam is turned and the lever 13 is oscillated. The movements of this feeding and also the discharge device, to be hereafter described, are so timed as to operate in proper unison with the forming mechanism. The upper end of the arm 13 is connected with a guided slide 14 having upwardly projecting sides or flanges with inclined edges or flanges as at 15'. This slide is reciprocated

beneath the pipe 5, and the upturned flanges 15' engage with cam-like arms 16 which are pivoted upon each side of the pipe 5 so that when the slides 14 move forward the front 5 end of the upturned flanges will engage with the lower ends of the arms 16 and will swing the arms so that the slides pass freely past the arms, and the ends of the slides will engage the edge of a veneer which has been already 10 brought down by the descent of the pipe 5. The veneer thus brought down rests upon guide plate 20, and as the slide 14 is moved inwardly, and the front edges of the upturned portions engage the veneer, the latter 15 will be pushed forward to its place on the former. It will be understood that this description of one of the devices applies to two which are placed at right angles with each other, as previously described. On the 20 return movement of the slide 14, the inclined edges 15' engage with the downwardly projecting arms or cams 16, and as the backward movement of these arms is limited by stops 16', it will be seen that the arms will ride up 25 on the inclines 15, thus raising the pipe 5 until the open mouth 6 is placed against the lowermost of the veneers 4, and on the upward movement, the valve 11 is opened through the action of the crank 12, the connecting rod 12^a and the oscillating arm 21 with which it is connected, and which is operated by a spur 22 projecting so as to be engaged by a part 23 of the cam 17, which is so timed that the valve will be opened at the instant 30 when the open suction mouth 6 is in contact with the veneers, and will be closed and the suction released, when the part has been depressed so as to place the veneer in position to be advanced to the former.

40 The forming of the basket is effected by the depression of the hollow rectangular frame B over the former A; this being effected by the action of a guided reciprocating arm 24 actuated by an oscillating lever 25, connecting rod 26 and cams or eccentrics upon the main shaft which are actuated in unison with the feed and discharge mechanisms, and at proper intervals in relation thereto. After the basket has been properly 45 formed, it is necessary to remove it from the former for the purpose of making room for the veneers for the next basket. This removal is effected as follows: 13^a is a lever fulcrumed at the opposite side of the machine from the lever 13, and pivoted at 14^a, and reciprocated in a manner similar to the lever 13 by the action of a cam 17^a mounted upon the shaft 18^a. The upper end of the lever 13^a is connected by a link 25' with a bar or shaft 26' which is 50 guided and slidable in boxes as at 27. This bar carries an arm or plate 28 which may be hinged to the revoluble sleeve 29 mounted upon the shaft 26', and turnable with the shaft as will be hereafter described. This

arm 28 is normally held up by a spring 30, 65 one end of which is connected with the part 28, and the other with a standard or support 31 which is carried upon the sleeve 29. The inner end of the arm or plate 28 has fixed to it an elastic plate 32 which has the upper flat 70 portion of a width approximately equal to the bottom of the folded veneers. The edges of this plate are turned downwardly, as shown, diverging so that when the plate is depressed as hereinafter described this part 75 32 will grasp the sides of the completed basket with sufficient frictional contact so that when again lifted it will lift the basket clear of the former, and as the rectangular part B has by this time been lifted clear out 80 of the former, there will be sufficient space for the withdrawal of the completed basket which is held by the friction of the elastic gripper 32. The withdrawal is effected by the oscillation of the lever 13^a and the sliding 85 of the shaft 26 in its bearings.

In order to deliver the baskets and pack them at the same time, guide rod 33 extends through slides 34 upon the revoluble sleeve 29. This guide rod is bent so that on the return movement of the lever 13^a, the part 29, the plate 28 and the gripper 32 are drawn back together, and by the curvature of the guide rod 33 these parts are turned so that at the instant of the completion of the rearward movement of the parts, the gripper and the basket carried thereby will have been turned to stand in position at approximately right angles with the position occupied when the basket was removed from the former. 90 The continuation of the movement then brings an arm 35, which projects from the side 29, into contact with a fixed stop 36 and this acts to swing the plate 28, the gripper 32 and the basket carried thereby, so as to place 95 the open mouth of the basket over the convergent bottom of the next preceding basket which has been placed in a convenient chute or receiver 37. Thus the baskets are constantly delivered into this chute, and pressed 100 one over another, being thus made into nests of any desired number, and ready for packing.

The gripper 32 is depressed after having been advanced to a position above the 115 former, by the contact of the downwardly projecting arm 35, with a fixed stop 35^a which thus acts to tilt the plate 28 and the gripper so as to force the latter down upon the basket with sufficient frictional force to 120 hold the basket so that the spring 30 will lift the gripper and basket when the parts commence to retract. It will be seen that the inclination of the former's sides and the interior of the basket is sufficient to allow the 125 simultaneous retraction and lifting of the basket during the above described movements.

Having thus described my invention, what I claim and desire to secure by Letters Patent is—

1. A device for transferring veneers and blanks, said device consisting of an oscillating vacuum tube having a suction opening in its movable part, and means to alternately place said opening in contact with a blank, and to withdraw the tube and blank, said means including a horizontally movable plate having side flanges with inclined edges, and pivoted members on the tube disposed in the range of action of the plate and adapted to ride upon the inclined edges of said plate as the plate is withdrawn to thereby raise the tube with its mouth in contact with a blank.
2. A device for transferring veneers and blanks, said device including a pivoted oscillating vacuum tube, having a suction mouth or opening at its movable end, a holder for blanks located in the line of movement of the suction mouth and means to place the opening in contact with a blank and to withdraw the tube and blank, said means including a horizontal slide having side flanges with inclined edges, and members pivotally mounted on the tube and having their free ends arranged in the path of movement of the slide, said members adapted, when the slide is withdrawn, to ride in contact with the inclined edges of the slide, whereby the tube is raised with its mouth in contact with a blank.
3. In a device for transferring veneers and blanks, a vacuum tube having a pivoted oscillating member with a suction mouth or opening, a blank-holder located in line of movement of the mouth, a valve, means by which it is opened to apply the vacuum when the mouth is in contact with a blank, and to release the vacuum after the blank has been withdrawn, and a slide movable in line with the released blank whereby the latter is removed from the transfer tube, said slide having raised sides with inclined top edges, and said tube having pivoted arms engaged by the slide and adapted to ride in contact with the inclined edges thereof.
4. In a device for transferring veneers and blanks, a tube connecting with a vacuum producing apparatus, a member pivoted to said tube having an opening or mouth in its movable part, a blank-holding device located in line of movement of said mouth, means for oscillating said movable member, said means including a horizontally movable plate having upturned and inclined edges, arms pivotally mounted upon the side of the oscillating tube, stops or shoulders upon the tube against which the arms contact when the slideable plate is withdrawn, said arms riding upon the inclines of the plate and acting to raise the oscillating tube with its mouth in contact with a blank.
5. In a device of the character described, a blank-holder, a vacuum tube having a jointed oscillating portion with a mouth at its movable end, means by which said tube is raised to bring the mouth into contact with a veneer, said means including a horizontal slide having raised sides with inclined top edges, and arms pivotally mounted on the tube and extending into the range of action of the slide, and having their lower ends to ride over the inclined edges of the sides of the slide, a valve located between the suction mouth and the vacuum producing apparatus to normally cut off connection with the mouth, a lever and mechanism whereby the valve is opened to allow the vacuum to act at the instant of contact with the blank, said valve being closed to cut off the vacuum after the blank has been withdrawn.
6. In a device for transferring veneers and blanks, a holder in which the blanks are retained by frictional contact, an oscillating arm, means by which it is alternately moved into contact with and away from the blanks, said means including a horizontal slide having raised sides with inclined top edges, and arms pivotally mounted on the tube and extending into the range of action of the slide, and having their lower ends to ride over the inclined edges of the sides of the slide, means by which said blanks are caused to successively adhere to the arm, actuating mechanism for the slide whereby said slide removes the blank after withdrawal from the holder, and means for breaking the adhesion of the blank to the arm before the movement of the slide.
7. In a device for transferring veneers and blanks, a vacuum tube having an oscillating member with a suction mouth, a holder in which blanks are retained by friction, a valve by which the suction mouth is normally cut off from the main tube, mechanism by which the oscillating member is moved to bring the mouth into contact with the blanks, said mechanism including a horizontal slide with side flanges having inclined top edges, pivoted arms on the tube having free ends to ride in contact with said inclined edges, and means for limiting the pivoting movement of the arms in one direction, and to simultaneously open the valve to cause an adhesion of the blank to the mouth, to withdraw the blank upon the return movement of the tube, to close the valve and cut off the vacuum, the flanges of said horizontal slide adapted to engage the rear edge of the blank after it has been released and to remove it from the suction tube.

In testimony whereof I have hereunto set my hand in presence of two subscribing witnesses.
